(57) **CLAIM**

The ornamental design for an adjustable storage bin, as shown and described.

DESCRIPTION

FIG. 1 is a perspective view of an adjustable storage bin;

FIG. 2 is a rear elevation view thereof;

FIG. 3 is a front elevation view thereof;

FIG. 4 is a right elevation view thereof;

FIG. 5 is a left elevation view thereof;

FIG. 6 is a top view thereof; and,

FIG. 7 is a bottom view thereof.

The broken lines in the drawings depict portions of the adjustable storage bin that form no part of the claimed design.
